UNITED STATES PATENT OFFICE.

HIRAM G. SEDGWICK, OF MILL VALLEY, CALIFORNIA; LOUIS BAETLETT, ADMINISTRATOR OF HIRAM G. SEDGWICK, DECEASED, ASSIGNOR TO THE NATIONAL SAFETY APPLIANCE COMPANY, A CORPORATION OF CALIFORNIA.

TRAIN STOP AND SIGNAL SYSTEM.

1,232,858.

Specification of Letters Patent. Patented July 10, 1917.

Application filed January 31, 1913. Serial No. 745,398.

To all whom it may concern:

Be it known that I, HIRAM G. SEDGWICK, a citizen of the United States, and a resident of Mill Valley, county of Marin, State of California, have invented certain new and useful Improvements in Train Stop and Signal Systems, of which the following is a full and clear specification, reference being had to the accompanying drawings, in which—

10 Figure 1 is a diagram of a sufficiently extensive portion of a road bed wiring to illustrate the application of my invention thereto;

Fig. 1^a a view showing a modification of 15 the invention;

Fig. 2 a similar view showing a further application or development of the invention;

20 Fig. 3 a diagram showing a still further application or development of the invention;

Figs. 4, 5 and 6 are detail views showing the tell-tale or safety circuit wires arranged in protective relation to other wires of the 25 local circuits.

This invention has relation to that class of signaling and stopping systems in which the rails are bonded and adapted to form parts of a normally closed block circuit, 30 which circuit is adapted to be weakened or opened by the entrance into the block of a railway vehicle, means being provided whereby when the track circuit is thus weakened or opened the railway signals will be 35 set to protect the block against the entrance of other railway vehicles into that block. In connection with this usual closed-circuit arrangement there is employed in some systems a supplemental means whereby the operation 40 of this main track circuit is relayed to supplemental train stopping or signaling devices on the road bed. An example of such supplemental system is shown in my co-pending application serially numbered 45 798,251, filed October 30, 1913. In connection with this system I have illustrated my present invention although it will be understood that this invention is applicable to other systems in which there is grafted on 50 the main track circuit one or more supplemental circuits which are adapted to operate train controlling devices on the road bed which are supplemental to any main signals, such as semaphores, which are

adapted to be operated by the main or track 55 circuit.

My present improvements have to do with the circuits of the supplemental train controlling devices, such for instance as the circuits which in the above-referred-to application are arranged to coöperate with certain electromagnets arranged on the road bed for the purpose of operating the signals or train stopping means on the locomotive. The object of the present invention is to provide means whereby should any of the local batteries become impaired by exhaustion or otherwise, or should any of the wires or other parts become impaired to an extent to render them inoperative, the main or track 60 circuit will be opened so that all the signaling or other train controlling devices which are connected directly or indirectly to the main or track circuit will be set in the same manner as they are set by the entrance of a 65 train into the block which they are arranged to protect, whereby as each train approaches a block it will receive the danger signals or be halted by the stopping means in case the block it is approaching has any of its 70 circuits or batteries out of order, so that in case the batteries or local wiring are inoperative in any block that block will be automatically preempted just as it is when a train enters upon it. In this way I get a very valuable 75 result, namely, that every train that passes over the road bed serves to test out the signaling and stopping means, thereby very greatly increasing the safety of the system, since throughout the railway system every 80 locomotive in use is testing out each block preparatory to entering the same, so that it will be practically impossible for any block to remain out of order for any appreciable 85 length of time without the derangement being brought to the attention of a train crew. 90

This object is accomplished in a very simple way, as more fully hereinafter set forth.

As above stated I have illustrated my present invention in connection with the 100 road bed system of wiring I have covered by my aforesaid co-pending application. I have illustrated but a fragment of the system as that will be amply sufficient for illustrating the nature of the present invention. 105

In the drawing annexed *a* designates the usual track battery, *b* the usual track magnet and *c* the conductors employed for stag-

gering around the insulated rail sections *d* and *e* so that the track circuit (comprising the battery *a*, magnet *b*, the rails of the block and the conductors *c*) will be normally closed until a train enters the block whereupon the magnet *b* will be short circuited and will be thus deenergized and caused to set into operation the usual signal devices on the road bed together with whatever supplemental signaling and stopping means that may be connected to the system.

One of these supplemental train control devices is shown at *f*, in the shape of an electromagnet mounted on the road bed adjacent to the insulated rails *d*. This magnet is included in a circuit *g* which contains a local battery *h* and a resistance *i*, this circuit being normally closed and the resistance *i* permitting but a slight part of the current of the battery to pass through the magnet wiring. The current that normally passes through the magnet *f* is not sufficient to energize it to a degree rendering it operative but when the resistance *i* is cut out the full force of the battery will be allowed to go through the magnet *f* and will thus energize it sufficiently to operate its companion armature on the locomotive as the locomotive passes over the magnet, said armature being connected up to devices which will either cause a signal or a train stopping device to be actuated.

Connecting the circuit *g* at one side of the resistance to one of the rails *d* is a conductor *j*, and connecting the circuit at the other side of the resistance to the other rail *d* is a conductor *k*. In this latter conductor is inserted an armature *l* which is held open by means of a relay *m*, whose circuit *n* is kept normally closed in any suitable manner, preferably as shown in my aforesaid co-pending application, so that the relay *m* normally attracts armature *l* and keeps partial circuit *k* open. Should a train enter the block ahead or should anything else be done to weaken or break circuit *n*, the relay *m* will be deenergized and the armature *l* will be released and permitted to close circuit *k*. Should a train then attempt to pass magnet *f*, the wheels and axles of the train would complete a circuit through conductors *j*, *k* and rails *d* and thus cut out the resistance *i* and allow the full battery charge to go into the magnet *f*, thereby energizing the magnet sufficiently to render it operative. The train that is passing will thus receive a signal or be stopped before it enters the block ahead.

It will be obvious from the foregoing that it is of the most vital importance that the battery *h* shall be in prime condition at all times and it is the main object of my present improvement to give warning of the exhaustion or impairment of the battery. For this purpose I tap the circuit *g* at either side of the battery with a circuit *o* and place there-

in a resistance *p* and a magnet *q*, this supplemental circuit *o* being at all times closed. The resistance *p* allows but a modicum of the current of the battery to pass through the magnet *q*. This magnet *q* will be sufficiently energized by this current to attract an armature *r* which is placed in a loop *s* of one of the stagger conductors *c* or is connected to one branch of the track circuit in any other manner, so that so long as the battery *h* is in good condition the magnet *q* will be energized and this branch of the track circuit will be kept closed. But upon impairment or exhaustion of the battery to a predetermined degree, the magnet *q* will be deenergized sufficiently to release armature *r* and thus break the track circuit. This breaking of the track circuit will bring about the same result as is brought about by the entrance of a train into the block, namely, will deenergize the track magnet *b* and thus actuate the usual signals and other train control devices in the block behind as well as in the block ahead. In this way the impairment of the battery results in preempting the adjacent block just as it is preempted when a train enters therein, so that it will be impossible for a train to pass through a block in which the local battery is impaired or exhausted.

In the conductor *j* is inserted a circuit breaker consisting of an armature lever *t* which is normally held closed by a suitable spring *u*. When a train passes off the rails *d* and onto the insulated rails *e*, this armature is attracted by a magnet *v*, thus opening circuit *j* and restoring the parts connected to the circuit *g* to normal, thus saving the battery *h* by throwing into the circuit *g* the resistance *i*. This magnet *v* may be energized in any suitable manner; I have shown means for energizing it in the same manner as in my aforesaid co-pending application. It will be observed that it is important that a warning be given in case of the derangement of this circuit breaker since if the partial circuit *j* be open the system will be inoperative. To obtain immediate warning of the impairment of the circuit closer *t*, I cut the protective circuit *o* and connect its ends, one to the armature *t* and the other to the circuit *j* beyond the armature, as shown in Fig. 2, so that the current in said circuit *o* will normally flow through the armature *t* and a part of the circuit *j*. In this way it will be obvious that should the partial circuit *j* be opened between the armature and its contact the circuit *o* will be likewise broken and will thus deenergize magnet *q* and cause the opening of the track circuit.

A modification of the system illustrated in Fig. 1 is shown in Fig. 1*. In this modification the magnet *q* is placed in a circuit *w* connected to the two branches of the circuit

g at a point close to the magnet f, so that a part of the current of circuit g will be permitted to pass through the circuit w and thus sufficiently energize the magnet q to hold armature r in its closed position. Proper precautions must be taken in this case to prevent the full charge of the battery, when magnet f is energized, entering circuit w. A suitable resistance may be employed for this purpose.

In Figs. 3, 4, 5 and 6 I illustrate a way of still further utilizing the closed circuit o. In this diagram a' designates a box in which is inclosed a battery h, resistance i, relay m, together with the resistance and magnet in circuit o. In the box illustrated at b' is inclosed the magnet v and its connected devices. The conductors o are arranged in protective relation to the conductors of the circuits g, j and k, so that should one of these conductors g, j and k be broken, the circuit o will also be ruptured and will thus deenergize the track magnet b, as above described. To secure this result the conductors o may be wrapped around the protected conductors g or they may be arranged on opposite sides of the same, as shown in Fig. 6 in which latter arrangement it is desirable that the conductors be embodied in a single cable, as shown. But it will be obvious that it is within the spirit of this part of my invention to greatly vary the manner of arranging the conductors o so long as they are arranged in a manner to mechanically protect the other conductors.

Having thus described my invention, what I claim as new and desire to secure by Letters Patent, is—

1. In a railway block system, a normally closed track circuit, a train control device on the road bed, a circuit including said device and a local battery, and means whereby the exhaustion or impairment of said battery opens the track circuit, said means consisting of a supplemental constantly closed circuit connected to said battery, a magnet in said circuit, and a circuit closer controlled by said magnet and located in the track circuit, whereby when said magnet is deenergized said track circuit will be opened.

2. A railway block signal system, including a normally closed track circuit, a train control device on the road bed, a closed local circuit including said train control device and a resistance and a local battery, means whereby the passing train shunts out

the resistance and lets the full force of the battery into the train control device when the block ahead is occupied, said means embodying a conductor connected to one of the rails, said conductor embodying a normally closed circuit closer, and supplemental devices whereby the exhaustion of the battery or the opening of said circuit closer will open the track circuit.

3. A railway block signal system, including a normally closed track circuit, a train control device on the road bed, a closed local circuit including said train control device, and a resistance and a local battery, means whereby the passing train shunts out the resistance and lets the full force of the battery into the train control device when the block ahead is occupied, said means embodying a conductor connected to one of the rails, said conductor embodying a normally closed circuit closer, and devices whereby the exhaustion of the battery or the opening of said circuit closer will open the track circuit, said devices consisting of a normally closed circuit connected to said battery and including said circuit closer and a resistance and a magnet.

4. In a railway block signaling or stopping system, the combination of a normally closed track circuit, a train control device on the road bed and means rendering said device operative independently of said track circuit, said means consisting of a local circuit and a local battery and suitable coöperating circuits, and means for opening the track circuit on the impairment of the local battery, said means embodying a supplemental closed circuit connected to said battery, the wires of this circuit being arranged in protective relation to the wires of the aforesaid circuits.

5. In a railway signaling or stopping system, the combination of a train control device on the road bed, a local battery and circuit for rendering the same operative, and means for indicating the exhaustion or impairment of said battery, said means embodying a normally closed supplemental circuit connected to said battery, the wires of this circuit being arranged in protective relation to the wires of the aforesaid circuit.

In testimony whereof I hereunto affix my signature in the presence of two witnesses.

HIRAM G. SEDGWICK.
